(57) **CLAIM**

The ornamental design for a vent for water heating device,
as shown and described.

DESCRIPTION

FIG. 1 is a front-left perspective view of a vent showing our
new design.

FIG. 2 is a front-right perspective view thereof.

FIG. 3 is a bottom-left perspective view thereof.

FIG. 4 is a bottom-right perspective view thereof.

FIG. 5 is a front view thereof.

FIG. 6 is a rear view thereof.

FIG. 7 is a left view thereof.

FIG. 8 is a right view thereof.

FIG. 9 is a top view thereof; and,

FIG. 10 is a bottom view thereof.

Any broken lines shown represent unclaimed subject matter
and form no part of the claimed design. Any shade lines
shown represent surface shading and not surface ornamen-
tation, color, or material type. The dot-dashed broken line
is included for the purpose of illustrating environmental struc-
ture and forms no part of the claimed design.

1 Claim, 10 Drawing Sheets
